MACHINE FOR OPERATING ON HEDDLES

Russell P. Drake, Caledonia, Ill., assignor to Barber-Colman Company, Rockford, Ill., a corporation of Illinois

Application November 30, 1945, Serial No. 631,994

13 Claims. (Cl. 28—46)

1

The invention pertains to a machine for operating upon heddles such as are used in loom harnesses or similar elements, and it has particular reference to a machine for operating upon steel heddles wherein a stack of heddles slidably supported in a heddle frame is successively released through the operation of a power driven shaft known as a release key shaft.

Steel heddles are commonly provided with centrally disposed apertures for the passage of the release key shaft, the slots being of keyhole shape for coaction with a key element on the shaft in effecting the successive release of the heddles in a warp drawing-in machine. The heddles as supplied by the manufacturer are intended to be so arranged that the slots of adjacent heddles extend in diametrically opposite directions with respect to the release key shaft so that in successive half revolutions of the shaft the heddles are released one by one. It frequently happens, however, that one or more of the heddles thus supplied are improperly positioned in the stack so that instead of releasing one heddle at a time, two or more heddles may be released.

The primary object of the present invention is to provide in a machine for operating on heddles means responsive to the release of more than one heddle and operative to interrupt the operation of the releasing means so that the improperly positioned heddle can be removed.

A further object is to provide a detecting means of the character set forth in a machine for operating upon the heddles preliminary to their transfer to a warp drawing-in machine and equipped with a counting mechanism so arranged as to afford a direct reading in terms of the number of heddles released.

An ancillary object is to provide a detecting means of the character aforesaid which is simple and effectual in operation and will not retard the heddle counting operation.

The objects of the invention thus generally set forth, together with other and ancillary advantages, are attained by the construction and arrangement shown by way of illustration in the accompanying drawings, in which:

Figure 1 is a fragmentary side elevational view of a heddle counter embodying my invention.

Fig. 2 is a front elevational view of the counter with a portion of the cover for the driving motor broken away to expose the control means.

Fig. 3 is a plan view of the control means on a somewhat enlarged scale, the cover being removed.

Fig. 4 is a horizontal sectional view on an en-

larged scale taken approximately in the plane of line 4—4 of Fig. 2.

Fig. 5 is a fragmentary vertical sectional view taken approximately in the plane of line 5—5 of Fig. 4.

Fig. 6 is a horizontal sectional view taken in the plane of line 6—6 of Fig. 2 but on an enlarged scale.

Fig. 7 is a fragmentary perspective view of a group of heddles shown in separated relation and illustrating the normal staggered relation of the keyhole slots in adjacent heddles.

In the present illustrative embodiment, my invention is applied to a heddle counter comprising an upright main frame 8 upon which a heddle frame 9 is adapted to be supported through the medium of pins 10 at opposite ends of a cross bar 11. At the upper end of the frame is a supporting plate 12 carrying a drive mechanism for a shaft 13 equipped with a chuck 14 in which is mounted a rotatable release key shaft 15. The heddle frame 9 carries a stack of heddles 16 slidably supported at their opposite ends and provided with central apertures 17 commonly in the form of keyhole slots. As shown in Fig. 7, the slots of adjacent heddles are staggered with respect to each other so that the narrow portions thereof project in opposite directions. The release key shaft 15 is inserted through aligned apertures 17 in the stack of heddles and the upper end of the key fastened in the chuck 14.

The lower end of the key shaft 15 is equipped with a spiral element or key 18 (Fig. 5) operative in a well known manner to release the heddles one at a time in the rotation of the shaft, the arrangement being such that in each half revolution of the shaft a heddle is released. 19 designates a backer also slidably supported in the heddle frame and serving to press the heddles downwardly against the key.

The drive mechanism comprises an electric motor 20 having a drive shaft 21 (Fig. 6) operating through gearing contained in a casing 22 to drive the release key shaft 15 and also a counter 23. As shown in Fig. 6, the drive shaft 21 carries a pinion 24 meshing with a gear 25 having a pinion 26 rigid therewith and meshing with a gear 27 on the shaft 13. A parallel shaft 28 carries a gear 29 meshing with the gear 27. This shaft 28 constitutes the drive shaft for the counter 23, the connection with the countershaft being through the medium of bevel gearing 30 (Fig. 1). It will be understood that upon rotation of the release key shaft 15 heddles are released at spaced intervals, one heddle being re-

leased at a time provided the heddles are properly arranged in the manner shown in Fig. 7 with the narrow portions of the keyhole slots 17 oppositely disposed.

Having in view the fact that the heddles supplied by the manufacturer are sometimes improperly arranged so that the keyhole slots of one or more adjacent heddles register with each other instead of being oppositely disposed as shown in Fig. 7, means is provided in accordance with the present invention for detecting the simultaneous release of two or more heddles. For this purpose, a support in the form of a slide 31 is arranged for operation in timed relation to the rotation of the release key shaft 15 so as to intercept the heddles upon release for a short interval of time, and associated with this slide is a feeler mechanism generally designated 32 for detecting the presence on the support of more than one heddle, the feeler mechanism being unresponsive to the deposit onto the support of a single heddle in the normal operation of the machine. Moreover, control means is provided which is operative in response to the actuation of the feeler mechanism to interrupt the operation of the drive mechanism so that the attendant can break out or remove the improperly positioned heddle or heddles, as the case may be.

In the present illustrative embodiment of the invention, the slide 31 is guided in ways 33 for movement in a direction perpendicular to the heddle release shaft 15 and in a plane immediately below the spiral key 18 (Fig. 5). As shown, the slide 31 has a lateral enlargement 34 at its forward end so as to provide a broad surface lengthwise of the heddle and movable into position beneath the stack of heddles in the heddle frame, the slide being provided with a slot 35 for the reception of the key shaft 15 as the slide is moved forwardly into position to intercept the heddles upon release by the key 18.

The slide is arranged for reciprocation by means of a cam 36 acting upon a lever 37 operatively associated with the slide. The cam is in the form of a disk fast on a driven shaft 38 and having a cam groove 39 for the reception of a roller follower 40 on the lever 37. The lever is pivoted at 41 and its connection with the slide is through the medium of a pin and slot connection 42. The cam and its associated parts may be supported upon the main frame in any suitable way. Herein a bracket 43 is mounted on the main frame for this purpose. This bracket is provided with guide bars 44 forming the ways 33 so that the slide 31 is also mounted on the bracket.

The cam shaft 38 extends upwardly (Fig. 2) for association with the drive mechanism at the upper end of the frame. As shown in Fig. 6, the shaft carries at its upper end a gear 45 meshing with the gear 27 on the shaft 13, the gear 45 being enclosed in the gear casing 22. The gear 45 has a 2:1 ratio with the gear 27 so that the cam shaft is driven through a complete revolution for each one-half revolution of the release key.

It will be understood that in the operation of the counter the slide is actuated by the cam 36 so as to carry the forward portion 34 of the slide into position between the stack of heddles so as to be capable of intercepting the heddles upon release by the key 18. For this purpose, the cam groove 39 is shaped so as to impart an initial advancing movement to the slide sufficient to carry the leading edge portion 34 into the position indicated at 34a in Fig. 5.

The feeler mechanism 32 comprises a lever arm 46 pivotally mounted on the slide so as to be movable therewith and carrying at its forward end a feeler element in the form of a roller 47 for coaction with the heddle or heddles deposited upon the slide. As shown (Fig. 4), the arm 46 is mounted on a web shaft 48 carried by the slide and urged by a torsion spring 49 in a direction to swing the arm 46 downwardly.

Following the initial advance of the slide into the position 34a an additional advancing movement is imparted thereto by the cam 36 (the cam groove 39 being appropriately shaped) so as to carry the roller 47 into feeling position with respect to the heddle or heddles temporarily resting upon the slide, it being observed that the heddles are held stationary during the advance of the slide by the lower projecting end of the shaft 15 passing through the aperture 17 of the heddle. Normally, that is to say, when a single heddle is positioned on the slide, the feeler roller 47 is ineffective. For this purpose, the roller is supported in an elevated position with respect to the slide so as to be capable of clearing a single heddle resting thereon. This is accomplished in the present instance by means of a depending portion or lug 50 rigid with the arm 46 and resting upon the slide. When two or more heddles have been released simultaneously and rest upon the slide, the roller becomes effective to impart a swinging movement to the lever which movement is utilized to interrupt the operation of the drive mechanism.

The control means whereby the drive mechanism is stopped by the operation of the feeler mechanism comprises in the present instance a switch 51 arranged for actuation by a plunger 52 slidably supported in the bracket 43 and underlying the rear or outer end portion of an arm 52a rigid with the shaft 48 and therefore with the lever arm 46. The switch is arranged to interrupt the circuit to the motor and at the same time control the operation of a brake mechanism generally designated 53 (Figs. 2 and 3) associated with the drive mechanism. This brake mechanism may be of any suitable or preferred character. By way of example, it may comprise a brake disk 54 rigid with the motor shaft 21 and coacting brake shoes 55 arranged for actuation by a spring 56 and held in disengaged position by a detent 57. The switch 51 is connected in series with a solenoid 58 which is normally energized, the arrangement being such that when the switch is opened and the solenoid deenergized, the detent 57 is actuated to release the brake shoes to the action of the spring 56.

In the operation of the counter, a heddle frame containing a stack of heddles is placed upon the main supporting frame 9 so as to be suspended from the pins 10 and the release key shaft 15 inserted through the aligned apertures 17 of the heddles and then fastened in the chuck 14 of the drive mechanism. A starting switch 59 (Figs. 2 and 6) is then closed to start the drive motor 20 so that the drive mechanism of the counter is set in motion. In the rotation of the release key shaft 15, heddles are released in rapid succession and as each heddle is released the counter 23 is correspondingly actuated. With a release means of the character herein shown, a heddle is released in each half revolution of the shaft 15 and in the interval occurring between successive releases, the slide 31 is actuated first to carry its leading edge portion

44 into position beneath the stack of heddles so as to be capable of intercepting the heddle next to be released, thereupon is advanced still farther so as to carry the feeler roller 47 of the detecting mechanism 32 forwardly over the released heddle, and finally retracted to drop the heddle. In its advance into feeling position, the roller is supported in spaced relation to the slide so as to clear the heddle, assuming that only one has been dropped under the slide. If, however, one or more adjacent heddles have been improperly arranged in the stack with respect to each other so that their apertures are in register with each other instead of alternating as shown in Fig. 7, the feeler mechanism operates in the final advance of the slide to engage the uppermost heddle. This will cause the lever 46 to swing on its pivot 48, depressing the plunger 52 and operating the switch 51. When this occurs, the brake 53 is applied to stop the drive mechanism, this occurring in the present instance through the opening of the switch 51 and de-energization of the solenoid 58 with a resultant release of the brake shoes to the operation of the spring 56. With the counter thus brought to rest, the improperly positioned heddle or heddles, as the case may be, are removed by the operator and the starting switch to the drive motor then closed to continue the operation.

It will be seen that through the use of a mechanism for detecting the simultaneous release of more than one heddle not only are the heddles counted accurately but improperly arranged heddles are detected, thereby insuring that when the heddle frame is placed in a warp drawing machine preliminary to its use in the loom the individual heddles will be properly arranged for successive release by the release mechanism of the warp drawing-in machine.

I claim as my invention:

1. A heddle counter comprising, in combination, a stationary upright frame adapted to support a heddle frame slidably supporting a stack of heddles having aligned apertures, a shaft adapted for insertion through the aligned apertures of the stack of heddles and having means operative upon rotation to release said heddles one by one, heddle counting means actuated in timed relation to said shaft, and means for detecting the simultaneous release of more than one heddle comprising a member reciprocable transversely of the release key, cam means operating in timed relation to the rotation of the release key to reciprocate said member into a position to receive the heddles upon release by said key and thence reversely to release the heddles, means operative while the heddles are supported on said member to detect the presence of a plurality of heddles thereon, and means controlled by the last mentioned means in response to the detection of a plurality of heddles to stop rotation of the release key.

2. In a heddle counter having means supporting a heddle frame in upright position with a stack of heddles slidably supported in the frame, motor driven means operative to release said heddles from said stack one by one, heddle counting means actuated by said motor driven means, means actuated by said motor driven means operative to interrupt the heddles upon release and supporting the same for a predetermined interval of time, and feeler means responsive to the presence of more than one heddle on such support to interrupt the operation of said releasing means.

3. In a heddle counter having means for sup-

porting a heddle frame in upright position with a stack of heddles slidably in the frame, means for releasing the heddles from said stack so as to cause them to drop by gravity one by one including a continuously rotating shaft operative to release heddles one by one and at predetermined intervals, heddle counting means connected with said shaft, feeler means operative in each such interval to detect the release of more than one heddle, and means controlled by said feeler means for interrupting the operation of said releasing means.

4. In an apparatus of the character set forth, means for supporting a heddle frame in upright position with a stack of heddles slidably supported in the frame, power driven means operative to release said heddles from said stack one by one, means operative in timed relation to the release of the heddles to intercept the same temporarily, feeler means operative to detect the simultaneous release of more than one heddle, and means controlled by said feeler means for stopping said releasing means.

5. In an apparatus of the character set forth, means supporting a heddle frame in upright position with a stack of heddles slidably supported in the frame, motor driven means operative to release said heddles from said stack one by one, and means operative in timed relation to said releasing means and responsive to the release of two or more heddles to open the circuit to the motor and to stop the rotation of the motor.

6. The combination of means supporting a heddle frame in upright position with a stack of heddles supported in the frame, means operative to release said heddles one by one from the stack, a slide reciprocable in timed relation to the release of the heddles and operative in the interval between the release of successive heddles to intercept temporarily the released heddles, feeler means operative in the movement of said slide to detect the interception of more than one heddle, and means operative by such feeler means for preventing the release of succeeding heddles.

7. The combination of means for supporting a heddle frame with a pack of heddles slidably supported in the frame, means normally operative to release said heddles from said pack one by one, a slide supported for reciprocation into position to stop the heddles upon their release, cam means operative in timed relation to the heddle releasing means for reciprocating said slide, and feeler means operative in the movement of the slide to detect the simultaneous release of more than one heddle.

8. The combination of means for supporting a heddle frame with a pack of heddles slidably supported in the frame, means normally operative to release said heddles from said pack one by one, a slide supported for reciprocation into position to interrupt the heddles upon their release, cam means operative in timed relation to the heddle releasing means for reciprocating said slide and feeler means actuated by the slide to detect the simultaneous release of more than one heddle, said feeler means comprising a member pivotally mounted on said slide, and a feeler element on said member normally supported in spaced relation thereto a distance approximately corresponding to the thickness of a single heddle but less than the thickness of two heddles.

9. A machine for operating upon heddles supported in a heddle frame and having aligned key-holes with the heddles normally arranged with

75 the keyholes of adjacent heddles in staggered re-

lation, a shaft inserted through the aligned apertures in the heddles and having a key thereon operative in each half revolution of the shaft to release a heddle, means for driving said shaft continuously, and means driven in timed relation to the rotation of said shaft and operative to detect a heddle improperly positioned in the frame with its keyhole in registry with that of the next preceding heddle.

10. In a machine for operating upon a stack of heddles slidably supported in a heddle frame and having aligned keyhole slots with the heddles normally disposed so that slots of adjacent heddles project in opposite directions, a shaft threaded through said holes and having a release key thereon operative in the rotation of the shaft to release heddles successively, means operating in timed relation to the rotation of said shaft for intercepting the heddles upon release by said key, and feeler means operative to detect the simultaneous release of two or more heddles having their keyhole slots in registering relation.

11. In a machine for operating upon a stack of heddles slidably supported in a heddle frame and having aligned keyhole slots with the heddles normally disposed so that slots of adjacent heddles project in opposite directions, a shaft threaded through said holes and having a release key thereon operative in the rotation of the shaft to release heddles successively, means operating in timed relation to the rotation of said shaft for intercepting the heddles upon release by said key, feeler means operative to detect the simultaneous release of two or more heddles having their keyhole slots in registering relation, and means operative by said detecting means for interrupting the rotation of said shaft.

12. In a machine of the character set forth, means for releasing heddles one by one from a

slidably supported stack, including a continuously rotating shaft perpendicular to the heddles, a slide reciprocable transversely of said shaft and operative upon the release of heddles from said stack into a position to intercept the same, and means operative in the movement of said slide into said intercepting position to detect simultaneous release onto the slide of a plurality of heddles.

13. In a machine of the character set forth, means for releasing heddles one by one from a slidably supported stack, including a continuously rotating shaft, a slide reciprocable transversely of said shaft and operative upon the release of heddles from said stack to intercept the same, and means operative to detect simultaneous release onto said slide of a plurality of heddles including a feeler mounted on the slide and cam means for reciprocating the slide and operative initially to advance the slide into its said intercepting position and upon the interception of the released heddles to continue the advance of the slide to carry said feeler into an advanced position over the intercepted heddles, and control means for said shaft actuated by said feeler.
